CLAIM

The ornamental design for a ganged RJ-45 interconnect, as shown and described.

DESCRIPTION

FIG. 1 is a perspective view of the ganged RJ-45 interconnect taken from the top and right.

FIG. 2 is another perspective view of the ganged RJ-45 interconnect taken from the bottom and left.

FIG. 3 is a front elevational view of the ganged RJ-45 interconnect.

FIG. 4 is a right elevational view of the ganged RJ-45 interconnect with the left side being a mirror image.

FIG. 5 is a rear elevational view of the ganged RJ-45 interconnect; and,

FIG. 6 is a top plan view of the ganged RJ-45 interconnect with the bottom being a mirror image.
